Primary Examiner — R. Johnson(74) *Attorney, Agent, or Firm* — MILLEN, WHITE, ZELANO & BRANIGAN, PC; Ryan Pool**CLAIM**

The ornamental design for a mandoline grip, as shown and described.

DESCRIPTION

FIG. 1 is a top perspective view of the mandoline grip showing my new design.

FIG. 2 is a front view thereof.

FIG. 3 is a back view thereof.

FIG. 4 is a side view thereof.

FIG. 5 is another side view thereof.

FIG. 6 is a top view thereof.

FIG. 7 is a bottom view thereof.

FIG. 8 is an exploded top perspective view in an environment of use; and,

FIG. 9 is a top perspective view in an environment of use. In FIGS. 8 and 9, the broken lines showing a mandoline illustrate the mandoline grip in use and form no part of the claimed design.
